UNITED STATES PATENT OFFICE.

JOSEPH E. DRAKE, OF BLUE RAPIDS, KANSAS.

GRAIN-CAR DOOR.

Application filed August 29, 1924. Serial No. 734,975.

To all whom it may concern...

Be it known that I, JOSEPH E. DRAKE, a citizen of the United States of America, and a resident of Blue Rapids, in the county of Marshall and State of Kansas, have invented a new and Improved Grain-Car Door, of which the following is a description:

My present invention has for its general object to provide an auxiliary grain car door to be employed beneath any approved main car door and adapted to be held at its ends to the sides of the door frame in a manner to be readily disengaged from the door frame for the purpose of removing said auxiliary door while leaving the main car door in position in the unloading of the grain car.

The present invention has specifically for an object to provide a construction of auxiliary door of the indicated character and of extreme simplicity and characterized by the facility with which the door may be emplaced and removed.

The nature of the invention and its distinguishing features and advantages will clearly appear as the description proceeds.

Reference is to be had to the accompanying drawings forming a part of this specification, it being understood that the drawings are merely illustrative of one example of the invention.

Figure 1 is a front elevation of an auxiliary grain car door embodying my invention showing the same emplaced in a door frame illustrated in part;

Figure 2 is a plan view of the auxiliary door, the door frame being in horizontal section as indicated by the line 2-2, Figure 1;

Figure 3 is a longitudinal vertical section in a plane indicated by the line 3-3, Figure 2;

Figures 4 and 5 are transverse vertical sections respectively on the lines 4-4 and 5-5 of Figure 1.

In the illustrated example the letter A indicates jambs of the door frame of a grain car, and B, the sill.

In accordance with my invention the auxiliary door is made with a body having inner and outer sides 10, 11 spaced at one end by an intervening elongated spacing element 12 the two sides and the intermediate element being held by bolts 13 hav-

ing polygonal nuts 14. At the inner face 55 of the inner side 10 of the auxiliary door are vertical strengthening and wear strips 15 of sheet metal against which the heads of the bolts 13 bear, there being similar strips 115 on the outer face of the element 11 60 against which the nuts 14 bear. At one end the auxiliary door is rabbeted as at 16, the rabbet extending through the outer side 11 and partially into the intermediate spacing element 12, the rabbeting resulting in a projecting end 17 adapted to be engaged with a jamb A of the door frame at the inner side as clearly shown in Figure 2 and indicated in dotted lines in Figures 1 and 3 at the left. At that end of the auxiliary door opposite the rabbet 16 and projecting end member 17, the inner member 10 advantageously extends beyond the outer member 11 to present an increased bearing surface to the grain when the car is loaded. Beyond the 70 spacing element 12 the inner and outer members 10 and 11 of the auxiliary door are separated by a space 18 in which space a locking slide 19 is disposed. Said locking slide 19 is formed with longitudinal slots 20 80 through which bolts 113 pass, said bolts being equipped with tail nuts 114, the tightening of which serves to bind the slide 19 between the spaced ends of the elements 10, 11 to hold said slide against movement when the auxiliary door is emplaced in the door frame.

The outer end of the locking slide 19 is provided with a strap 21 returned on itself and spaced to receive the reduced end 119 90 of the slide 19. Rivets 22 or equivalent fastening means hold the strap 21 in place. The extreme outer end of the strap 21 has its sides thereof flattened into close relation in a manner to provide in effect a rabbet 23 95 so that the flattened end of the strap may be engaged with the adjacent jamb A of the door as in Figure 2. To guide and assist in preventing vertical displacement of the slide 19 I form a rib and groove engagement between the slide and the member 10 or 11. In the illustrated example a longitudinal rib 24 is formed on the member 10 at the inner face and a longitudinal groove 25 in slide 19 accommodating said rib. The strips 15 and 115 are employed at the bolts 113 and tail nuts 114 in the same manner as with the bolts 13 and nuts 14.

On the locking slide 19 at the outer face is a projection 26 against which a stick or other lever may be engaged in prying the slide 19 loose from its engagement with the jamb A.

In Figure 3 it will be seen that the slide 19 is formed at its rear end at the top with the tongue 119. Said tongue 119 is received in a longitudinal cut-out 112 in the spacing element 12. The end of the tongue 119 is chamfered as at 219 for the purpose of preventing the grain that enters the cut-out 112 from jamming the tongue 119. With the above described construction the auxiliary door is emplaced by engaging the projecting member 17 at one end behind the adjacent jamb A. The auxiliary door is then brought into the plane of the doorway and the slide 19 is moved outwardly sufficient to enter the projecting end formed by the strap 21 at the back of the opposite jamb A, whereupon the tail nuts 114 are tightened up to hold the auxiliary door in position with both ends engaged with the jambs. To remove the auxiliary door the tail nuts 114 or equivalent nuts are turned back sufficiently to release the slide 19 and permit movement of said slide in the space 18 toward the element 12. A suitable lever such as any convenient stick or bar is now placed against projection 26 and pressure exerted against the adjacent jamb A to disengage the strap 21 from said jamb whereby the pressure of the grain within the car will press the release end of the auxiliary door outwardly, permitting said door to be readily removed. It is to be understood that the main car door (not shown) is emplaced at the proper time and in the proper manner in the loading of the car and nailed in position as is customary.

I would state in conclusion that while the illustrated example constitutes a practical embodiment of my invention, I do not limit myself strictly to the exact details herein illustrated, since, manifestly, the same can be considerably varied without departure from the spirit of the invention as defined in the appended claims.

Having thus described my invention, I claim:

1. An auxiliary grain car door adapted to be positioned beneath the main door of a car, said auxiliary door including a body, and a locking slide movable longitudinally of the body to vary the total effective length of the auxiliary door, said body at one end and said slide at the opposite end of the door having members to engage the door frame at the inner side; together with a tongue on said slide at the inner end at the top of the slide, the body of the door having a cut-out in which said tongue is movable, said tongue

being chamfered to dislodge any grain entering said cut-out. 65

2. An auxiliary grain car door adapted to be positioned beneath the main door of a car, said auxiliary door including a body having front and back elements presenting at one end a space therebetween, and a locking slide movable longitudinally of the body in said space to vary the total effective length of the auxiliary door, said body at one end and said slide at the opposite end of the door having members to engage the door frame at the inner side, one of said elements of the body and the opposed surface of the slide presenting respectively a longitudinal rib and a groove receiving the rib preventing vertical displacement of the locking slide. 70 75

3. An auxiliary grain car door adapted to be positioned beneath the main door of a car, said auxiliary door including a body having front and back elements presenting at one end a space therebetween, and a locking slide movable longitudinally of the body in said space to vary the total effective length of the auxiliary door, said body at one end and said slide at the opposite end of the door having members to engage the door frame at the inner side; together with transverse bolts passing through said spaced body members, and said slide and nuts on the bolts adapted to be tightened up to bind said spaced body elements against the locking slide to hold the latter in adjusted position. 80 85 90

4. An auxiliary grain car door adapted to be positioned beneath the main door and including a body and a locking slide movable longitudinally of the body to vary the total effective length of the auxiliary door, said body at one end being rabbeted to present a projecting member adapted to engage the car door frame at the inner side, and a strap 100 on the end of said slide and flattened at its outer end to present essentially a rabbeted formation, said strap adapted to engage a side of the door frame at the inner side. 105

5. An auxiliary grain car door adapted to be positioned beneath the main door and including a body and a locking slide movable longitudinally of the body to vary the total effective length of the auxiliary door, said body at one end being rabbeted to present a projecting member adapted to engage the car door frame at the inner side, and a strap 110 on the end of said slide and flattened at its outer end to present essentially a rabbeted formation, said strap adapted to engage a side of the door frame at the inner side; together with a projecting member on the front face of said strap adapted to be engaged by a pry for disengaging the strap from the door frame. 115 120
